UNITED STATES PATENT OFFICE.

GUSTAF ELLSTROM, OF FITCHBURG, MASSACHUSETTS, ASSIGNOR TO
MARY E. JOHNSON, (EXECUTRIX,) TRUSTEE, OF FITCHBURG, MAS-
SACHUSETTS.

BREAKDOWN GUN.

No. 832,660.

Specification of Letters Patent.

Patented Oct. 9, 1906.

Application filed February 16, 1904. Serial No. 193,769.

To all whom it may concern:

Be it known that I, GUSTAF ELLSTROM, a citizen of the United States, residing at Fitchburg, in the county of Worcester and State of Massachusetts, have invented a new and useful Breakdown Gun, of which the following is a specification.

This invention relates to a breech-loading firearm of the breakdown type.

10 The object of this invention is to provide a strong, simple, and efficient action for a breakdown firearm in which a single trigger controls the barrel-catch as well as the firing mechanism; and the especial object of this invention is to combine the parts in an action 15 of the kind referred to so that the weapon cannot be accidentally discharged by the closing of the barrel should the gun have been cocked when the barrel is open.

20 To these ends this invention consists of the construction and combinations of parts, as hereinafter described, and more particularly pointed out in the claims at the end of this specification.

25 In the accompanying drawings, Figure 1 is a fragmentary side view, partly broken away, of a breakdown firearm constructed according to this invention, showing the firing mechanism cocked and ready for discharge; and Fig. 2 is a similar view showing the parts in normal or half-cocked position, which is normally assumed by the parts after the gun is fired.

30 In that class of firearms to which this invention relates it has heretofore been proposed to provide a construction in which a single trigger is used for controlling the firing mechanism as well as the barrel-catch. In actual practice I have found the use of a connection between the barrel-catch and the trigger would be dangerous unless some provision is made for preventing the discharge of the firearm by the closing of the barrel should the gun be cocked while the barrel is open—that is to say, unless some provision is made to prevent such an accident the closing of the barrel by forcing back the trigger would release the hammer should the hammer happen to have been raised while the gun is open.

35 The special object of my present invention is to provide a stop mechanism for preventing the accidental discharge of a gun of the class referred to by the closing of its barrel.

In the specific construction herein illustrated 55 this is accomplished by providing the barrel-catch and the hammer with coöperating projections, which will prevent the barrel-catch from being forced back by the closing of the barrel when the hammer is in raised position. 60

A further object of this invention is to provide a simplified action of the kind referred to in which a less number of parts will be used than in previous actions of this type.

Referring to the accompanying drawings 65 and in detail, A designates the frame of a breakdown firearm, and B designates the barrel, which is pivoted to turn or swing upon a pin 10. The barrel B is provided with the ordinary barrel-lug, which is notched at its 70 rear end to coöperate with the barrel-catch 11. The barrel-catch 11 is pivoted upon a cross-pin 12. The barrel-catch 11 is held in normal position to engage and lock the barrel in closed position by a flat spring 13. The 75 barrel-catch 11 is slabbed or milled away at its sides. Pivotaly mounted upon the same cross-pin 12 as the barrel-catch and straddling the barrel-catch is the trigger 14. The trigger 14 has a lost-motion connection with 80 the barrel-catch 11 by means of a pin 15 engaging a short slot in the barrel-catch, as indicated by dotted lines. The trigger is held in its forward position by a small coiled spring 16.

85 Pivotaly mounted on a cross-pin 18 is the hammer 17. The hammer 17 is provided at its lower edge with two notches for coöperating with a detent or sear 20, which is normally forced up to engage the hammer by a 90 small coiled spring 21. The sear 20 is notched or V-shaped at its forward end, and the trigger 14 is provided with a projection 22, coöperating with the V-shaped end of the sear. The hammer may be operated by the 95 usual spring-pressed plunger 19 to have a rebounding or normally half-cocked action in the ordinary manner.

100 In the operation of a firearm as thus constructed, when the parts occupy their normal position, as illustrated in Fig. 2, the sear is far enough up out of the way of the trigger so that a full stroke may be given to the trigger, drawing back the barrel-catch 11 and releasing the barrel, so that the same will 105 open for reloading. On the other hand, when the hammer is drawn back to cocked position, as illustrated in Fig. 1, the end of the sear

will be moved down in the path of the projection 22 on the trigger, so that a short movement or partial stroke of the trigger will release the hammer and discharge the gun. At 5 the same time the V-shaped end of the sear will form a stop for limiting the stroke of the trigger and preventing the same from being pulled far enough to release the barrel until the sear 20 is again permitted to move up out 10 of the way, as shown in Fig. 2. Considering now what would happen should the gun be cocked while the barrel is open, it will be seen that the pushing back of the barrel-catch by the closure of the gun would also force back 15 the trigger and would discharge the gun were no provision made for preventing this action from taking place.

In a firearm constructed according to this invention I have provided means for preventing 20 the barrel-catch from being forced back by the barrel when the hammer is raised at a time when the gun is open. To accomplish this purpose, as illustrated in the drawings, the barrel-catch 11 is provided with a projection 25 25, which co-operates with a projection of the hammer 17. When the parts occupy the normal position, as shown in Fig. 2, the projection 23 may be swung back into the recess or notch in the front of the hammer 17; but 30 when the hammer 17 is raised, as illustrated in Fig. 1, the lower part of the hammer forms a stop or abutment which by engagement with the projection 23 will prevent the barrel-catch from being forced back. This provides 35 efficient means for preventing accidental discharge of the gun by the closing of the barrel.

I am aware that changes may be made in the construction of breakdown guns by those 40 who are skilled in the art without departing from the scope of my invention as expressed in the claims. I do not wish, therefore, to be limited to the special construction I have herein shown and described; but

What I do claim, and desire to secure by 45 Letters Patent of the United States, is—

1. In a breech-loading firearm, the combination of the frame, a barrel, a catch for the barrel mounted to be normally forced back by the barrel when it is being closed, a firing 50 mechanism, a trigger connected to operate both the firing mechanism and the barrel-catch, and means for preventing the barrel-catch from being forced back by the barrel should the firing mechanism be cocked while 55 the gun is open.

2. In a breech-loading firearm, the combination of the frame, a barrel, a catch for the barrel mounted to be normally forced back by the barrel when it is closed, a hammer, a 60 sear for holding the hammer in raised position, and a trigger connected to release the sear when the hammer is raised, or to draw the barrel-catch back when the gun is to be opened, the barrel-catch and hammer having 65 projections co-operating to prevent the barrel-catch from being forced back by the barrel should the hammer be raised while the gun is open.

3. In a breech-loading firearm, the combination of a hammer, a barrel-catch, a trigger pivoted concentrically with the barrel-catch and having a lost-motion connection therewith, and a sear co-operating with the hammer and moved down into position to be 70 released by the initial movement of the trigger when the hammer is raised, the barrel-catch and hammer having projections co-operating to prevent the barrel-catch from being forced back by the barrel should the hammer be raised while the gun is open. 75

In testimony whereof I have hereunto set my hand in the presence of two subscribing witnesses.

GUSTAF ELLSTROM.
